UNITED STATES PATENT OFFICE.

SAMUEL ZIED, OF PHILADELPHIA, PENNSYLVANIA.

MOVABLE DERRICK-CRANE IN CONNECTION WITH MOTOR-TRUCKS.

1,165,483.

Specification of Letters Patent. Patented Dec. 28, 1915.

Application filed July 8, 1915. Serial No. 38,746.

To all whom it may concern:

Be it known that I, SAMUEL ZIED, a citizen of the United States, residing at Philadelphia, in the county of Philadelphia and State of Pennsylvania, have invented certain new and useful Improvements in Movable Derrick-Cranes in Connection with Motor-Trucks, of which the following is a specification.

10 My invention relates to improvements in derrick cranes, the object of the invention being to provide an improved construction of boom with an improved mounting therefor, which enables the boom to be adjusted longitudinally during the operation of the apparatus, and which permits a full control of the bucket or other load.

20 A further object is to provide a derrick crane of the character stated, in which the entire operation can be controlled from a single motor shaft, and which will embody in its construction various novel details which together result in an apparatus which efficiently performs the functions for which 25 it is intended.

With these and other objects in view, the invention consists in certain novel features of construction and combinations and arrangements of parts as will be more fully hereininafter described and pointed out in the 30 claims.

In the accompanying drawings: Figure 1 is a view in side elevation illustrating my improved derrick crane on a motor vehicle. Fig. 2 is a top plan view of Fig. 1, the bucket being removed for purposes of clearness. Fig. 3 is a view in transverse section on the line 3—3 of Fig. 1, the post being shown partly in elevation and partly in section. 40 Fig. 4 is a view in section on the line 4—4 of Fig. 1. Fig. 5 is a view in transverse section on the line 5—5 of Fig. 2. Fig. 6 is a broken view in side elevation illustrating my improved boom, and Fig. 7 is an enlarged view in transverse section on the line 7—7 of Fig. 6.

1 represents a motor vehicle which is driven by a motor 2, and 3 is a second motor located on top of the vehicle 1, and both of 50 said motors supplied by the necessary current from a storage battery 4.

It is, of course, to be understood that my invention is not limited to any particular means for driving the vehicle, but as a convenient means I preferably employ elec-

tricity, and utilize the same for driving the vehicle and for operating my improved derrick crane as will now be described.

5 represents a vertical post which is mounted to turn in a bearing 6 in the vehicle 60 floor 7, and is strengthened by stays 8 which are secured to a ring 9 located at the upper end of the post, and in which the post freely turns. A strap 10 is fixed to the post 5, and is provided with a pivot bolt 11 pivotally 65 connecting my improved boom 12 to the post. This strap 10 is so constructed as to allow a free passage of the cables which will be hereinafter described. A ring 13 is mounted to turn on the end of the post 5, and a ring 14 is mounted to turn on the lower end 70 of the post 5. These rings 13 and 14 support a plurality of pulleys 15 and 16 respectively.

My improved boom 12 shown most clearly in Figs. 6 and 7, comprises two members 12^a and 12^b. The member 12^a is of general M shape in cross section, while the member 12^b is of general inverted N shape, so that the two parallel longitudinal webs of the member 12^b will rest between the webs of the 80 member 12^a, thus both of the members have their webs positioned edgewise, and impart the maximum of strength to the boom. The members are movable relative to each other, and slide freely when operated. 85

A U-shaped band 17 is secured to the upper end of the member 12^a, and has a roller 18 at its open end on which the member 12^b rolls. This band with its roller maintains the members together, assisted by the load, 90 and at the free end of member 12^b a pulley 20 is located, while a pulley 21 is secured to the side of member 12^a adjacent its free end. Member 12^b has an eye 22 adjacent its lower end, and band 19 is provided with an eye 95 23 at its upper end.

The motor 3 above referred to, drives a shaft 24 containing a plurality of drums 25, 26, 27, 28 and 29 respectively. These drums may, of course, be variously controlled, so 100 that each drum may be independently operated, and while I have made no attempt to cover any specific construction for controlling the drums, I have illustrated more or less diagrammatically levers 30 which can 105 be operated to control the drums.

A relatively large wheel or turn table 31 is secured to the post at its lower end, and a cable 32 is positioned around this wheel, and connected to the drums 28 and 29, so 110

that by the operation of the said drums, the post with its boom may be turned in both directions.

A cable 33 is secured to the eye 23, is passed around certain of the pulleys 15 and 16 on the rings 13 and 14 respectively, and secured to the drum 26. A cable 34 supports at its free end a bucket or other load 35, is passed over the pulley 20 on the free end of the boom 12, and thence over pulleys 15 and 16 of rings 13 and 14, and secured to drum 25.

A cable 36 is secured to the eye 22 of boom member 12^b, is passed over the pulley 21, thence over pulleys 15 and 16 of the rings 13 and 14, and secured to the drum 27. When the pull is had on cable 36, it operates to move the boom member 12^b longitudinally relative to the member 12^a, causing the boom to lengthen, and this operation can be performed either during the lifting operation or at any intermediate point in the operation.

Cable 33 operates to raise and lower the boom, cable 34 to raise and lower the load, and cable 32 to turn the crane so as to position the load as desired.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a derrick crane, the combination with a post, of a boom pivotally connected to the post and comprising two members, each of said members comprising a single integral metal bar having parallel webs located side by side with the webs positioned edgewise to support the load, and means for moving one of said members relative to the other, substantially as described.

2. In a derrick crane, the combination with a post, of a boom pivotally connected to the post and comprising two members, each of said members comprising a single integral metal bar having parallel webs located side by side with the webs positioned

edgewise to support the load, a pulley on the free end of one of said members, a load supporting cable located on said pulley, and means for moving the pulley carrying member relative to the other member, substantially as described.

3. In a derrick crane, the combination with a post, of a boom pivotally connected to the post and comprising two members, each of said members comprising a single integral metal bar having parallel webs located side by side with the webs positioned edgewise to support the load, a pulley on the free end of one of said members, a load supporting cable located on said pulley, a cable connected to said movable member of the boom and adapted to move the same longitudinally, and a third cable connected to the boom and adapted to raise and lower the same, substantially as described.

4. In a derrick crane, the combination with a post, of a boom pivotally connected to the post, said boom comprising two members, one member of general M shape in cross section, the other member of inverted N shape in cross section with the webs of the two members located side by side, means for moving one member relative to the other, and means for raising and lowering and swinging the boom laterally, substantially as described.

5. The combination with a movable support, of a post having rotary mounting thereon, a boom pivotally connected to the post, said boom comprising two members, one member of general M-shape in cross section, the other member of inverted N-shape in cross section with the webs of the two members located side by side, a drum shaft on said support containing a plurality of drums, cables connected to said drums, one of said cables connected to the boom for raising and lowering the same, another supported on the boom and operating as a load support, and another of said cables adapted to turn the post, substantially as described.

In testimony whereof I have signed my name to this specification in the presence of two subscribing witnesses.

SAMUEL ZIED.
